poration of Indiana

Application March 31, 1939, Serial No. 265,070

4 Claims. (Cl. 229—37)

This invention relates to cartons or fiber board boxes of that type which are formed in flat blanks and then folded to be set up and enclosed by overlapping flaps requiring adhesive to retain the flaps in closed positions.

5 A primary object of the invention is to form a carton or box in such manner that in the process of manufacture the adhesive may be applied to all of the required flaps in a single operation by passing the carton in flat form through the usual and well known type of adhesive applying machines whereby the adhesive is applied at both ends of the box on extending flat ends.

10 15 A still further important object of the invention is to provide a box with overlapping sealing flaps which have a plastic adhesive carried thereby forming a permanent seal upon contact of one adhesively coated flap over another adhesively coated flap, and yet permitting the box to be stacked one over another in flat form with the adhesive sides of the flaps of one box being contacted with the non-adhesive sides of the flaps of another box, all without any 20 25 tendency for the adhesive to adhere to the next adjacent box.

The invention permits the forming of a box that may be shipped in flat form with the adhesive already applied to the sealing flaps of such a character that all that is required of the user is to press one flap over the other to complete the sealing operation without further application of adhesive or without having to heat or moisten the adhesive.

30 35 It is a further important object of the invention to form an exceedingly simple blank for a box of the above indicated characteristics, which blank may be produced without complicated dies or cutting work.

40 45 These and other objects and advantages of the invention will become apparent to those versed in the art in the following description of one particular form of the invention as illustrated in the accompanying drawings, in which:

45 Fig. 1 is a top plan view of a blank;

Fig. 2, a top plan view of the blank following its initial folding operation and following the application of the adhesive;

50 55 Fig. 3, an end elevation of the blank in that form as shown in Fig. 2;

Fig. 4, a view in perspective of the box as further set up from the form as shown in Figs. 2 and 3;

55 Fig. 5, a front elevation with the under-side

of the box closed and the upper end partially closed; and

Fig. 6, an end elevation of the completed box.

Like characters of reference indicate like parts throughout the several views in the drawings.

5 Referring first to Fig. 1, a blank is formed to have a central rectangular portion ABCD and this portion is divided into front, back and end panels by the score lines EF, GH, and IJ. Extending integrally, respectively from both the top and bottom lines of the panel AEFD are the tongues 10 and 15. From the end panel EGHF extend integrally, respectively the tongues 16 and 17, both being identical in dimensions and each extending outwardly further than the adjacent shorter tongues 10 and 15.

10 15 From the next panel GIJH extend integrally therefrom the respective tongues 18 and 19, both tongues extending outwardly to the same distance as do the tongues 16 and 17. From the next adjacent panel IBCJ integrally extend therefrom the tongues 20 and 21 a distance equal to that of the tongues 10 and 15. The tongues are each separated one from the adjacent tongues by cuts through the blank so that each tongue may hinge independently of the other tongue from the top and bottom edges respectively of the major portion of the blank, these top and bottom lines preferably being score lines across the junctions of the respective tongues and panels, that is, the lines AB and DC are preferably defined by score lines. A laterally extending tongue 22 extends from the outer marginal end AD of the central blank portion, the blank being preferably scored along the line AD to permit ready bending of the tongue along that line.

20 25 30 35 The blank thus formed, Fig. 1, is then folded along the score lines EF and IJ to bring the lateral tongue 22 over on top of the panel GIJH and have the panel IBCJ lap over on top of the tongue 22 and be adhesively united therewith.

40 45 50 55 While the box blank is in this flattened form, adhesive is applied across both ends outwardly from the lines EI and FJ to coat both tongues 10 and 20 and the protruding ends of the tongues 16 and 18 at the one end and the tongues 15 and 21 as well as the protruding ends of the tongues 17 and 19 at the other end, Fig. 2. This adhesive is preferably a latex, either natural or synthetic, which may be applied, as indicated, to the various tongues in a liquid state to dry somewhat rather quickly and then be non-adhering to a non-coated blank part when placed thereover, but will very securely adhere to the

adhesive of another coated part when pressed thereover.

- Following the adhesive application step, the box is ready for shipment or delivery to the user who sets up the box by pushing on the edges EF and IJ to carry the blank, Fig. 3, into box-shape as shown in Fig. 4, with the various tongues extending outwardly from the side and end panels. As indicated in Fig. 5, the tongue 20 is bent inwardly and the tongue 16 is folded thereover to have the adhesive coating of the tongue 16 contact with the coating on the tongue 20 so that these two members may then become adhesively united thereby.
- Next, the tongue 10 is folded over the tongues 16 and 20 and the tongue 18 is folded down over the tongue 10 to have the two adhesive surfaces contact one another to form the bond or seal so as to retain the tongues in the closed positions. It is to be noted that in the particular dimensions selected for the example herein, the tongue 16 does not reach entirely across the tongue 20 but that the tongue 18 does come entirely across over the tongue 10 to the line EA so that all of the adhesive coating of the tongue 10 is completely covered. The tongues on the other end of the box are similarly carried to the closed positions and adhesively retained in those positions by first bringing the tongue 21 inwardly and the tongue 17 thereover, followed by folding in the tongue 15 and then folding the tongue 19 over the tongue 15.

As above indicated, the particular form of box herein illustrated and described is but one possible example of the invention. It is obvious that the proportions of the sides and ends may be varied and also the particular shapes of the overlapping tongues. Furthermore it is immaterial whether the lateral tongue 22 extends from the line AD or extends from the other end of the blank from the line BC, and it, therefore, becomes obvious that structural variations may be employed without departing from the spirit of the invention and I, therefore, do not desire to be limited to the precise form herein shown and described beyond the limitations as may be imposed by the following claims.

I claim:

1. For a set-up carton, a folded carton blank having side wall sections consecutively connected one with the other along corner fold lines, said blank being flattened to have two adjacent side wall sections overlapping and resting on two other adjacent side wall sections thereunder, each of said sections having a tongue extending respectively from its top and bottom ends, the tongues extending from said under adjacent sections being longer than said upper tongues to have end portions exposed beyond the overlapping upper tongues, and a plastic adhesive on and limited to the exposed end portions of said

under tongues and also on the upper faces of the upper tongues.

2. For a set-up carton, a folded carton blank having side wall sections consecutively connected one with the other along corner fold lines, said blank being flattened to have two adjacent side wall sections overlapping and resting on two other adjacent side wall sections thereunder, each of said sections having a tongue extending respectively from its top and bottom ends, the tongues extending from said under adjacent sections being longer than said upper tongues to have end portions exposed beyond the overlapping upper tongues, and a plastic adhesive on and limited to the exposed end portions of said under tongues and also on the upper faces of the upper tongues, said adhesive being characterized by tenacious adherence to said tongues when applied, but, following a drying period, remaining plastic and bonding securely with like adhesive, while having substantially no permanent adhesion with surfaces uncoated with the adhesive, whereby the blanks with adhesive coated tongues may be stacked one on the other for storage and shipping, and the blanks be eventually folded into cartons with the longer tongues folded over onto the shorter tongues to bring the adhesive surfaces together for bonding and forming sealed carton end walls.

3. For a set-up carton, a folded carton blank having side wall sections consecutively connected one with the other along corner fold lines, said blank being flattened to have two adjacent side wall sections overlapping and resting on two other adjacent side wall sections thereunder, each of said sections having a tongue extending respectively from its top and bottom ends, the tongues extending from said under adjacent sections being longer than said upper tongues to have end portions exposed beyond the overlapping upper tongues, and a plastic adhesive on and limited to the exposed end portions of said under tongues and also on the upper faces of the upper tongues at least adjacent their respective side wall sections, said adhesive being latex.

4. For a set-up carton, a folded carton blank having side wall sections consecutively connected one with the other along corner fold lines, said blank being flattened to have two adjacent side wall sections overlapping and resting on two other adjacent side wall sections thereunder, each of said sections having a tongue extending respectively from its top and bottom ends, the tongues extending from said under adjacent sections being longer than said upper tongues to have end portions exposed beyond the overlapping upper tongues, and a plastic adhesive on and limited to the exposed end portions of said under tongues and also on the upper faces of the upper tongues, over the entire area thereof.

HARRY H. LINDLEY.
